CLAIM

(21) Appl. No.: **29/402,693**

The ornamental design for a right-angle coaxial cable connector, as shown and described.

(22) Filed: **Sep. 26, 2011**

DESCRIPTION

(51) **LOC (9) Cl. 13-03**

FIG. 1 is a front perspective view of a right-angle coaxial cable connector showing my new design;

(52) **U.S. Cl. D13/151**

FIG. 2 is a back perspective view thereof;

(58) **Field of Classification Search** D13/151,

FIG. 3 is a left side elevation view thereof, with the right side elevation being a mirror image;

D13/133, 149, 150, 153, 154, 156, 184, 199;

307/10.1; 333/81 A, 81 R; 411/7, 11, 190;

439/180, 296, 321, 322, 345, 578-585, 656,

439/660, 666, 686

FIG. 4 is a top plan view thereof;

See application file for complete search history.

FIG. 5 is a bottom plan view thereof;

FIG. 6 is a front elevation view thereof;

FIG. 7 is a back elevation view thereof;

FIG. 8 is a front perspective view thereof, shown in an alter-

native environmental use; and,

FIG. 9 is a front perspective view thereof, shown in another

alternate environmental use.

The broken line portion of the figure drawings is included for

the purpose of illustrating environment and forms no part of

the claimed design.
